DESIGN FOR A CHAIR

Alexey Brodovitch, New York, N. Y.

Application June 24, 1942, Serial No. 107,331

Term of patent 7 years

To all whom it may concern:

Be it known, that I, Alexey Brodovitch, a citizen of the United States of America and a resident of the city, county, and State of New York, have invented a new, original, and ornamental Design for a Chair, of which the following is a specification, reference being had to the accompanying drawing, forming part thereof, and which is a perspective view of a chair, showing my design.

I claim:

The ornamental design for a chair, substantially as shown.

ALEXEY BRODOVITCH.
